UNITED STATES PATENT OFFICE.

ALFRED SHEDLOCK, OF JERSEY CITY, NEW JERSEY, ASSIGNOR TO I. B.
KLEINERT RUBBER COMPANY, OF NEW YORK, N. Y., A CORPORATION
OF WEST VIRGINIA.

CLASP.

No. 829,175.

Specification of Letters Patent.

Patented Aug. 21, 1906.

Application filed March 24, 1906. Serial No. 307,768.

To all whom it may concern:

Be it known that I, ALFRED SHEDLOCK, a citizen of the United States, and a resident of Jersey City, Hudson county, State of New Jersey, have invented Improvements in Clasps, of which the following is a specification.

The clasp forming the subject of this invention is designed to grip and hold fabrics and is particularly adapted for use as the holding device of garment-supporters. It embodies the principle of operation of the clasp patented to me November 30, 1897, No. 594,568.

15 In the accompanying drawings, forming part of this specification, which are drawn to a scale greater than the device would be when used as a garment-supporter, Figure 1 is a front view of a clasp complete embracing the features of this invention. Fig. 2 is a vertical central sectional view of the same. Fig. 3 is a longitudinal section of the interior gripping member or button of the clasp. Fig. 4 is a plan view of the button-plate. Fig. 5 is a longitudinal section of Fig. 4. Fig. 6 is a transverse section of Fig. 3, and Fig. 7 is a transverse section of Fig. 4.

The essential feature of this invention resides in the construction and mode of manufacture of the interior gripping member of the clasp or button, which consists of a block *a*, having grooves *b* formed in its sides, inclined or converging from the upper to the lower end of the block, the lower end thereof being rounded and grooved in continuation of the side grooves *b*. This block *a* is of a material, preferably celluloid, adapted to be molded into the desired shape and to provide an anchorage or locking means therefor, and to economize by using the least possible amount of the molding material a metal core is provided in the form of a box *c*, so shaped and sized as to occupy most of the interior of the block *a*, leaving sufficient only of the molded material to form the complete active exterior of said block or button and adapt it to perform its functions as a gripping member of the clasp. The box-core *c* is with the exception of its open under side entirely surrounded by the material of the block *a*, and from the edges of the sides of the box-core *c* extend lugs *d*, which are pointed, as shown at Fig. 3, portions of said edges being above or within the base surface of the block, thus

providing gates for the overflow of the material while being molded to enter the interior of the core *c*, as indicated at *e*, Figs. 3 and 6. This enables the article to be molded in practically-closed molds with the least possible waste of material and to be ready for use when molded. The portions of the molded material which extend into the gate-openings act to lock the hollow core firmly in the button. This button *a* is designed to be attached to a webbing or fabric, and to enable this to be effectually done a plate *f* is provided, having openings or perforations *g* made through it corresponding to the positions of the lugs *d* of the button. The central part of the plate *f* between the perforations *g* is depressed, as shown at *h*, Figs. 5 and 7, this depressed portion being of a size to enter the open face of the box *c*.

The manner in which the block or button *a* is secured to a fabric is as follows, it being shown at Figs. 1 and 2 attached to a piece of webbing *i*, such as is used in garment-supporters of ordinary make: The plate *f* is placed beneath the webbing *i* at a suitable distance from its end, and the block *a* is located above the webbing with its lugs *d* in alinement with the perforations *g* of the plate. The parts are then pressed together, causing the pointed lugs *d* to puncture the webbing and pass through the perforations of the plate *f*, their ends being then bent down into the recess *h* of the plate. The webbing is then folded around the lower edge of the plate, which may be roughened or serrated, as shown, to afford a grip on the webbing and hold the plate fixed relative thereto and over the back of the plate and its end secured to the main portion of the webbing just above the top edge of the plate. By this means the block is securely attached to the webbing, the plate *f* entirely covered with the least possible folds of the webbing, the thickness of this portion of the clasp being a minimum, as shown at Fig. 2. This block or button is designed to be used with the other member of the clasp in the form of a loop having an opening in its upper part large enough for the button with the fabric to be clasped surrounding it to pass through and having inclined straight converging sides below said opening to cooperate with the grooves *b* in the sides of the button to grip and hold the fabric with an increasing force as the strain on the fabric in-

creases. The loop may be made in any desirable way. It is shown as made of wire bent at the lower end, with upwardly-extending straight sides *j* of a length equal to or in excess of the length of the sides of the button. The wire then turns outwardly and upwardly, as at *k*, to form the opening for the button, and the ends are then bent toward each other to form the top bar *l*, but are left disconnected to afford springiness to the loop for the accommodation and effectual gripping of different fabrics. The loop and the webbing *i* may be secured together in any suitable manner, a simple way being to insert the bar *l* of the loop in a fold of the webbing and secure the parts together by sewing, as illustrated at Figs. 1 and 2.

The block or button may be made of any plastic material that will set hard when molded. Celluloid has been found to be most suitable for the purpose, as it may be easily and quickly formed into the desired shape and by reason of the variety of colors in which it is made is particularly useful in producing artistic effects.

I claim as my invention—

1. A clasp, comprising a button having inclined grooved sides, a metal hollow box-core around which the button is formed or molded and having projections extending beyond the bottom of the button, a plate having perforations through which the projections of the box-core are adapted to pass, whereby said button is adapted to be secured to a fabric by its projections passing therethrough and through the perforations of the plate and then bent or riveted over against the bottom of the plate, in combination with a loop whose sides converge forming gripping-surfaces with which the grooved sides of the button coöperate to grip a fabric between them.

2. A clasp-button composed of a moldable material, as celluloid, and a box-core having an open side at the bottom of the button with portions of its edges within the surface of the button constituting gates for the entrance to the interior of the core of the overflow of the material as it is molded, and having fastening-lugs extending from the edges outside of the bottom surface of the button.

3. In a clasp, the combination of a button composed of a moldable material, as celluloid, a box-core having an open side at the bottom of the button with lugs projecting from its edges beyond the bottom of the button, a plate recessed centrally forming a raised portion adapted to enter the opening in the bottom of the button-and its box-core and having perforations to receive the lugs of the box-core, whose ends when bent over to lock the button to the plate lie in the recess of the plate.

4. In a clasp, the combination with a button having inclined grooved sides and an open-side box-core with lugs extending from the bottom of the button; a plate with raised center and perforations through which the lugs of the button pass; a webbing between the bottom of the button and the plate pressed into the opening of the button by the raised center of the plate, the points of the lugs being bent over into the recess of the raised center of the plate; and a loop attached to the webbing and having converging sides to form coacting gripping-surfaces with the inclined grooves of the button.

In testimony whereof I have hereunto subscribed my name this 22d day of March, 1906.

ALFRED SHEDLOCK.

In presence of—

J. C. MCKIBBIN,

JAMES A. HUDSON
